(57) **CLAIM**

The ornamental design for a tool stand, as shown and described.

DESCRIPTION

FIG. 1 is a perspective view of a first embodiment of a tool stand showing the design of the invention.

FIG. 2 is a front view thereof.

FIG. 3 is a rear view thereof.

FIG. 4 is a side view thereof, the opposite side being a mirror image.

FIG. 5 is a top view thereof.

FIG. 6 is a bottom view thereof.

FIG. 7 is another perspective view thereof showing the tool stand in use, when standing.

FIG. 8 is a perspective view of a second embodiment of a tool stand, showing the design.

FIG. 9 is a front view thereof.

FIG. 10 is a rear view thereof.

FIG. 11 is a side view thereof, the opposite side being a mirror image.

FIG. 12 is a top view thereof.

FIG. 13 is a bottom view thereof.

FIG. 14 is another perspective view thereof, showing the tool stand in use, when standing.

FIG. 15 is a perspective view of a third embodiment of a tool stand, showing the design.

FIG. 16 is a front view thereof.

FIG. 17 is a rear view thereof.

FIG. 18 is a side view thereof, the opposite side being a mirror image.

FIG. 19 is a top view thereof.

FIG. 20 is a bottom view thereof.

FIG. 21 is another perspective view thereof showing the tool stand in use, when standing.

FIG. 22 is a perspective view of a fourth embodiment of a tool stand, showing the design.

(Continued)

FIG. 23 is a front view thereof.

FIG. 24 is a rear view thereof.

FIG. 25 is a side view thereof, the opposite side being a mirror image.

FIG. 26 is a top view thereof.

FIG. 27 is a bottom view thereof.

FIG. 28 is another perspective view thereof showing the tool stand in use, when standing.

FIG. 29 is a perspective view of a fifth embodiment of a tool stand, showing of the design.

FIG. 30 is a front view thereof.

FIG. 31 is a rear view thereof.

FIG. 32 is a side view thereof, the opposite side being a mirror image.

FIG. 33 is a top view thereof.

FIG. 34 is a bottom view thereof.

FIG. 35 is another perspective view thereof, showing the tool stand in use when standing.

FIG. 36 is a perspective view of a sixth embodiment of a tool stand, showing the design.

FIG. 37 is a front view thereof.

FIG. 38 is a rear view thereof.

FIG. 39 is a side view thereof, the opposite side being a mirror image.

FIG. 40 is a top view thereof.

FIG. 41 is a bottom view thereof.

FIG. 42 is another perspective view thereof, showing the tool stand in use, when standing.

FIG. 43 is a perspective view of a seventh embodiment of a tool stand, showing the design.

FIG. 44 is a front view thereof.

FIG. 45 is a rear view thereof.

FIG. 46 is a side view thereof, the opposite side being a mirror image.

FIG. 47 is a top view thereof.

FIG. 48 is a bottom view thereof.

FIG. 49 is another perspective view thereof showing the tool stand in use, when standing.

FIG. 50 is a perspective view of an eighth embodiment of a tool stand, showing the design.

FIG. 51 is a front view thereof.

FIG. 52 is a rear view thereof.

FIG. 53 is a side view thereof, the opposite side being a mirror image.

FIG. 54 is a top view thereof.

FIG. 55 is a bottom view thereof; and,

FIG. 56 is another perspective view thereof showing the tool stand in use, when standing.

The broken lines showing of rakes and hoes in the drawings represent environment and form no part of the claimed design. The remaining broken lines in the drawings depict

portions of the tool stand and form no part of the claimed design.
